CLAIM

The ornamental design for a combined vehicle bumper
and storage trunk, as shown and described.

DESCRIPTION

FIG. 1 is a right front perspective view of a combined
vehicle bumper and storage trunk in accordance with
our new design, the cover of the trunk being shown in
open condition;

FIG. 2 is a top plan view thereof;

FIG. 3 is a front elevation view thereof; and,

FIG. 4 is a left end elevation view thereof.

The bottom and rear of the combined vehicle bumper
and storage trunk are flat and unornamented.

FIG. 1

FIG. 2

FIG. 3

FIG. 4
